NO. 11,248

JUNE 17, 1879

UNITED STATES PATENT OFFICE.

ALBERT C. FAIRBANKS, OF BOSTON, MASSACHUSETTS.

DESIGN FOR RUBBER FOUNTAIN-SYRINGE.

Specification forming part of Design No. **11,248**, dated June 17, 1879; application filed March 27, 1879.
[Term of patent 7 years.]

To all whom it may concern:

Be it known that I, ALBERT C. FAIRBANKS, of Boston, in the county of Suffolk and State of Massachusetts, have invented a new and original Design or Configuration and Shape for a Rubber Fountain-Syringe, of which the following is a full, clear, and exact description, reference being had to the accompanying photographic illustration, making part of this specification.

The nature of my design is fully represented in the accompanying photographic illustration, to which reference is made.

A represents the body of the syringe, of an oblong form, having two parallel vertical edges, B B, and four segmental or rounded corners, C C C C, the two lower ones being extended upon their bottom edges to their junction with the outlet-tube D, and the two top corners forming an "ogee," in conjunction with the neck G, forming the curves, as shown. The edges shown in the said outline formed by the parts or portions represented by the letters B and C have affixed an ornamental binding, E, having imi-

tation of rows of stitching, the neck G having a re-enforced piece, H, extending down upon the body A and terminating in a point, F, and having imitation of stitching in two rows. At the lower portion of the body is a re-enforce piece, L, extending from the tube D upward, and terminating in a point, as shown, and having imitation of two rows of stitching, the design consisting in the new shape and in the configuration shown therewith.

What I claim is—

The design for a rubber fountain-syringe, consisting of the oblong body A, having the segmental corners C, the upper ones forming an ogee, in connection with the neck G, having the re-enforce piece H, terminating in the point F, and the lower or bottom portion having the re-enforce L, the edges B C, having the binding E, stitched as represented.

ALBERT C. FAIRBANKS.
